(No Model.)

C. P. WEISS.
SAND BOX FOR LOCOMOTIVES.

No. 605,803.

Patented June 14, 1898.

Fig. 2.

UNITED STATES PATENT OFFICE.

CHARLES P. WEISS, OF HORNELLSVILLE, NEW YORK.

SAND-BOX FOR LOCOMOTIVES.

SPECIFICATION forming part of Letters Patent No. 605,803, dated June 14, 1898.

Application filed January 26, 1898. Serial No. 668,053. (No model.)

To all whom it may concern:

Be it known that I, CHARLES P. WEISS, a citizen of the United States, residing at Hornellsburg, in the county of Steuben and State 5 of New York, have invented certain new and useful Improvements in Sand-Boxes for Locomotives; and I do hereby declare the following to be a full, clear, and exact description of the invention, such as will enable others skilled in the art to which it appertains 10 to make and use the same.

My invention relates to sand-boxes for locomotives; and its object is to provide improved means under the control of the engineer for blowing the sand through the sand-openings for distributing it on the track.

The invention consists, essentially, in locating an air-blast pipe in the sand-box provided with nozzles in close proximity to the sand-openings, which communicate with the pipes which carry the sand to the track, and the cock of said air-pipe being so connected with the lever for operating the sand-valves that the latter will be opened in advance of 25 the said cock, as will be hereinafter fully described and claimed.

In the accompanying drawings, Figure 1 is a side elevation of a locomotive sand-box, showing my improvements applied thereto,

30 Fig. 2 is a transverse sectional view. Fig. 3 is a detail view of the T-coupling. Fig. 4 is a detail view of the lever mechanism.

In the said drawings, the reference-numeral 1 designates the locomotive-boiler, and 2 the 35 sand-box, formed with chambers 3 at opposite sides, the inner walls of which are provided with sand-openings 4. These chambers communicate with the pipes 5, leading to the rails.

40 The numeral 6 designates rotatable valves secured to the shaft 7, provided with a crank 8, connected by a rod 9 with the operating lever 10 under control of the engineer. These valves are formed with openings 12, adapted 45 to coincide with the openings 4 when the lever 10 is operated to sand the tracks. The parts so far described may be of any ordinary or suitable construction, as in themselves they form no part of my invention. Also 50 located in said box and supported by brack-

ets 13 is a curved pipe 14, made in two sections, the inner ends of which are connected by a T-coupling 15 and the outer ends formed or provided with nozzles 16, so disposed as to point directly toward the sand-openings. 55 The said T-coupling is also provided with a rearwardly-extending pipe 17, connected with a compressed air reservoir (not shown) and provided with a stop-cock 18, the stem of which is provided with a crank 19, connected by a rod 20 with the sand-lever 10. This cock is so constructed that the sand-valves will be opened in advance thereof, so that if the sand-openings are not clogged or congested the air blast or current will not be 65 turned on; but if said passages are clogged then a further pull upon the lever will open the cock, so that air-jets will be directed in the sand-openings, cleaning the same and causing the sand to be carried down to the 70 rails.

I do not limit myself to any particular location of the sand-openings, and they may be formed in the bottom of the sand-box, nor do I wish to be confined to any particular construction and arrangement of the sand-valves, 75 as the invention may be employed in connection with any of the sand-boxes now in general use.

Having thus described my invention, what 80 I claim is—

In a sand-box for locomotives provided with sand-openings and sand-pipes leading therefrom, of sand-valves controlling said openings, an operating-lever, connection between 85 said valves and lever, an air-jet pipe located within the sand-box and having nozzles arranged in line with the sand-openings, an air-supply pipe communicating with the jet-pipe and provided with a valve, a rod connection 90 between said valve and the operating-lever, whereby the air-pipe valve is adapted to be opened by said lever after the latter has opened the sand-valves.

In testimony whereof I affix my signature 95 in presence of two witnesses.

CHARLES P. WEISS.

Witnesses:

H. K. BROWN,
MILES W. HAWLEY.
